CLAIM

The ornamental design for an electrical outlet adapter,
as shown.

DESCRIPTION

FIG. 1 is a rear perspective view of the electrical outlet adaptor, showing my new design.

FIG. 2 is a front elevational view thereof;

FIG. 3 is a rear elevational view thereof;

FIG. 4 is a top plan view thereof;

FIG. 5 is a side elevational view thereof, the opposite
side being a mirror image.

FIG. 6 is a bottom plan view of the electrical outlet
adaptor.
